CIRCUIT INTERRUPTING DEVICE

Benjamin W. Jones and Otto R. Schurig, Schenectady, N. Y., assignors to General Electric Company, a corporation of New York

Application March 11, 1943, Serial No. 478,784

6 Claims. (Cl. 200—120)

Our invention relates to circuit interrupting devices and more particularly to circuit interrupting devices employing a fusible element and used for protecting electrical apparatus of the liquid insulation filled type such as motor starters, transformers and the like.

Electrical apparatus, such as motor starters, transformers and the like often comprise a casing or container filled with an insulating dielectric such as oil or the like. In order to protect such apparatus, it would be desirable to provide devices which could be mounted within the container or casing, preferably immersed in the dielectric which devices are simple and inexpensive, and would operate to give complete protection to the apparatus under both moderate and high overload conditions.

Our invention is particularly concerned with a new and improved oil immersed fuse and has for its principal object such a fuse embodying the features enumerated above.

It is another object of our invention to provide a new and improved fuse of the oil immersed type which operates on the oil blast principle and effectively interrupts the current under both moderate and high overload conditions.

Further objects and advantages of our invention will become apparent as the following description proceeds and the features of novelty which characterize our invention will be pointed out with particularity in the claims annexed to and forming a part of this specification.

For a better understanding of our invention, reference may be had to the accompanying drawing in which Fig. 1 is a schematic diagram partly in section illustrating an application of oil immersed fuses embodying our invention, Fig. 2 is an enlarged view partly in section of a fuse embodying our invention, Fig. 3 is a sectional view taken on line 3—3 of Fig. 2, Fig. 4 is a sectional view taken on line 4—4 of Fig. 2, Fig. 5 is a partial view of the fuse of Fig. 2 taken along line 5—5 of Fig. 2 and Fig. 6 is a sectional view of a fuse showing a modification of our invention.

Although the circuit interrupting device of our invention is applicable for protecting any liquid insulation filled type of apparatus, we have chosen to illustrate it in Fig. 1 as applied to an oil immersed contactor generally indicated at 10. Oil immersed contactor 10 comprises a casing 11 filled with an insulating dielectric such as oil 12. Mounted within casing 11 is a contactor schematically indicated at 13. Contactor 13 may be a single phase or a polyphase apparatus, protected by one or more fuses 14 embodying our invention.

One fuse 14 is connected in series with each phase of the contactor and these fuses are completely immersed in oil as indicated in Fig. 1.

The oil immersed fuses 14 of Fig. 1 may take the form illustrated in Figs. 2 to 5, comprising an insulating casing 15. At the upper end of casing 15 is an upper fuse terminal 16. Similarly, at the lower end of casing 15 is a lower fuse terminal 17. Each of these terminals 16 and 17 are provided with an opening 18 so that electrical connections by bolting or the like may be made with associated circuits as indicated in Fig. 1. The construction of upper and lower fuse terminals 16 and 17 forms no part of our invention and may comprise any suitable form which will permit ready assembly with casing 15. In order to hold the terminals in position at the ends of casing 15 we provide upper and lower terminal caps 19 and 20 respectively which are each provided with a central opening 21 through which fuse terminals 16 and 17 may extend.

Interconnecting fuse terminals 16 and 17 is a fuse link generally indicated at 22. Fuse link 22 is provided with an upper fusible element 23 and a lower fusible element 24 each provided with one or more portions of reduced cross-section 25 indicated best in Fig. 5. Under high overload conditions the fuse link 22 will rupture at one of these portions of reduced cross-section to interrupt the circuit therethrough. Fuse links of this type have a fairly high melting temperature well above the lowest temperature at which an insulating dielectric such as oil is damaged or decomposed and under low overload current conditions when the rate of heating is slow, difficulties would be encountered in melting this link preparatory to interrupting the circuit. To this end our new and improved fuse link 22 comprises a central section which includes a pair of conducting members such as upper member 26 and lower member 27 preferably constructed of copper or the like. The upper member 26 is connected by suitable means as indicated at 28 with the upper fusible element 23 while the lower member 27 is connected by similar means 29 with lower fusible element 24. The adjacent ends of the members 26 and 27 are soldered together as indicated at 29. Preferably this solder has a relatively low melting point compared to the temperature at which the fusible elements 23 and 24 of fuse link 25 will rupture. However, the mass of members 26 and 27 are large so as to conduct heat away from solder 29 and the melting time of solder 29 may be controlled by a proper proportioning of the associated parts.

In order to cause high speed separation of the adjacent ends of the members 26 and 27 upon melting of the solder 29, we have provided means including a spring 30 which engages with an insulating pin member 31 suitably fastened to the lower end of upper member 26 and normally extending through an opening 32 in lower member 27 and surrounded by solder 29. Upon melting of the solder 29 spring 30 will force pin 31 to move through the opening 32 in lower member 27 and cause relative separation between members 26 and 27 so as to interrupt the circuit. With this arrangement a sort of time lag feature is provided on moderate overload currents which would not cause the fusible portions 23 and 24 of fuse link 22 to rupture at the restricted portions 25.

In order to be sure that satisfactory interruption of the circuit occurs on relatively high currents, we have discovered that by providing one or more openings 33 in the walls of casing 15 adjacent the restricted portions 25 of fuse link 22, a very effective oil blast action takes place upon rupture of the fuse link. These openings 33 permit the immediate escape of oil and gases from the fuse tube or casing 15 so as to provide an oil blast effect whereby the extinction of the arc is accelerated. We have discovered that these openings should be relatively large to perform satisfactorily with the desired oil blast effect. We have also discovered that in fuses such as have been described above, convection currents cause a high convection effect between the liquid dielectric in the fuse casing 15 and the surrounding dielectric 12 in casing 11 of Fig. 1. This convection effect will tend to cool the fuse link so that the desired operating characteristics are not obtained. We have found that by providing a mechanically weak covering such as a puncturable or frangible closure member over the openings 33 such convection currents are stopped and yet at the same time the escape of oil through the openings as soon as the closure member is punctured upon the occurrence of a moderate pressure within the casing 15 is permitted. By covering the openings 33 the convection currents which would remove heat from the fusible element so rapidly that an abnormally high wattage would be required to bring the fuse link to its melting point at moderate overload currents is prevented.

These closure members might take any suitable form and as illustrated in the drawing may comprise a wrapping 34 of cloth, paper, or some equivalent material. We have illustrated these closure members as a complete wrapping around the casing 15 but it should be understood that small puncturable closure members might be provided for each individual opening so long as they prevent convection currents and yet permit an effective oil blast action.

A small bleed hole 17 is provided in lower fuse terminal 11 so that under normal current carrying conditions an equalization of pressure inside and outside of casing 15 is permitted. Temperature changes due to normal load current carried by fuse link 22 will therefore not cause an increase of pressure in casing 15 to rupture wrapping 34.

In view of the detailed description included above, the operation of the oil immersed fuse of our invention will be obvious and no further discussion thereof will be included hereinafter.

In Fig. 6 we have illustrated a fuse 14' which is a modification of our invention which modification goes only to the terminals of the fuse and the fuse link itself. These have been designated

with the same reference numerals as in Fig. 2 marked with a prime. The other corresponding parts of Fig. 6 are, furthermore, designated with the same reference numerals as in Fig. 2. Fusible link 22' of Fig. 6 comprises two fusible elements 35 and 36 respectively including portions of reduced cross-section 37 which are mounted opposite oil blast openings 33 so as to operate in the same manner as the fuse described above. The fusible elements 35 and 36 of fuse link 22' are soldered together by a low melting point solder 38 substantially identical with the low melting point solder 29 of Fig. 2. The elements 35 and 36 respectively are provided with spring biasing members 39 and 40 constantly tending to bias these members apart so as to assume the dotted positions indicated in Fig. 6. Under moderate overload conditions the solder 38 will eventually melt so as to cause separation of the fuse link parts 35 and 36 with the consequent interruption of the current flowing therethrough. Under high overcurrent conditions, on the other hand, the fuse link 22' will rupture at one of the restricted portions 37 and the arc drawn will be rapidly extinguished by the oil blast action similar to that described in connection with the fuse 14 of Fig. 2.

From the above description it will be obvious that we have provided a new and improved oil immersed fuse which will operate very effectively both at high and low currents. Furthermore, this fuse is simple and compact and readily adaptable for use with apparatus such as oil immersed contactors, transformers or the like.

While we have described preferred embodiments of our invention, it will be obvious to those skilled in the art that various changes may be made without departing from our invention and we, therefore, aim in the appended claims to cover all such changes and modifications as fall within the true spirit and scope of our invention.

What we claim as new and desire to secure by Letters Patent of the United States is:

1. In an electric fuse of the type adapted to be immersed in a liquid insulating dielectric such as oil and capable of interrupting satisfactorily both high and low currents comprising a casing, a pair of terminals associated with said casing, a fuse link interconnecting said terminals comprising a restricted portion adapted to rupture upon high overcurrents and a soldered joint adapted to melt after a time delay upon moderate overcurrents, and means comprising an opening in said casing adjacent said restricted portion of said fuse link to permit an oil blast action to interrupt the current flowing in said fuse upon rupture of said fuse link at said restricted portion.

2. In an electric fuse of the type adapted to be immersed in a liquid insulating dielectric such as oil and capable of interrupting satisfactorily both high and low currents comprising a casing, a pair of terminals associated with said casing, a fuse link interconnecting said terminals comprising a restricted portion adapted to rupture upon high overcurrents and a soldered joint adapted to melt after a time delay upon moderate overcurrents, means comprising an opening in said casing adjacent said restricted portion of said fuse link to permit an oil blast action to interrupt the current flowing in said fuse upon rupture of said fuse link at said restricted portion, and means for preventing said insulating dielectric from circulating through said opening to cool said fuse link under normal operating conditions.

3. In an electric fuse of the type adapted to be immersed in a liquid insulating dielectric such as oil and capable of interrupting satisfactorily both high and low currents comprising a casing, a pair of terminals associated with said casing, a fuse link interconnecting said terminals comprising a restricted portion adapted to rupture upon high overcurrents and a soldered joint adapted to melt after a time delay upon moderate overcurrents, means for causing separation of said soldered joint upon melting thereof to interrupt the current flowing through said fuse, and means comprising an opening in said casing adjacent said restricted portion of said fuse link to permit an oil blast action to interrupt the current flowing in said fuse upon rupture of said fuse link at said restricted portion.

4. In an electric fuse of the type adapted to be immersed in a liquid insulating dielectric such as oil and capable of interrupting satisfactorily both high and low currents comprising a casing, a pair of terminals associated with said casing, a fuse link interconnecting said terminals comprising a restricted portion adapted to rupture upon high overcurrents and a soldered joint adapted to melt after a time delay upon moderate overcurrents, spring means for causing separation of said soldered joint upon melting thereof to interrupt the current flowing through said fuse, and means comprising an opening in said casing adjacent said restricted portion of said fuse link to permit an oil blast action to interrupt the current flowing in said fuse upon rupture of said fuse link at said restricted portion.

5. In an electric fuse of the type adapted to be immersed in a liquid insulating dielectric such as oil and capable of interrupting satisfactorily both high and low currents comprising a casing,

5 a pair of terminals associated with said casing, a fuse link interconnecting said terminals comprising a restricted portion adapted to rupture upon high overcurrents and a soldered joint adapted to melt after a time delay upon moderate overcurrents, means for causing separation of said soldered joint upon melting thereof to interrupt the current flowing through said fuse, means comprising an opening in said casing adjacent said restricted portion of said fuse link to permit an oil blast action to interrupt the current flowing in said fuse upon rupture of said fuse link at said restricted portion, and means for preventing said insulating dielectric from circulating through said opening to cool said fuse link under normal operating conditions.

10 6. In an electric fuse of the type adapted to be immersed in a liquid insulating dielectric such as oil and capable of interrupting satisfactorily both high and low currents comprising a casing, a pair of terminals associated with said casing, a fuse link interconnecting said terminals comprising a restricted portion adapted to rupture upon high overcurrents and a soldered joint adapted to melt after a time delay upon moderate overcurrents, spring means for causing separation of said soldered joint upon melting thereof to interrupt the current flowing through said fuse, means comprising an opening in said casing adjacent said restricted portion of said fuse link to permit an oil blast action to interrupt the current flowing in said fuse upon rupture of said fuse link at said restricted portion, and means for preventing said insulating dielectric from circulating through said opening to cool said fuse link under normal operating conditions.
